UNITED STATES PATENT OFFICE

2,602,400

BURIAL VAULT HANDLING APPARATUS

Wilbert W. Haase, Forest Park, Ill.

Application September 13, 1947, Serial No. 773,859

1 Claim. (Cl. 104—126)

1

This invention relates to burial vault handling apparatus. More particularly, this invention relates to apparatus for handling concrete burial vaults at the grave openings in cemeteries.

The burial vault handling apparatus which forms the subject matter of the present application is in the nature of an improvement upon certain features of construction which are disclosed and claimed in the U. S. Patent No. 2,537,812, issued January 9, 1951, to Walter Boehme.

The handling of concrete burial vaults at grave openings in cemeteries has heretofore been a difficult and laborious operation which has customarily required the services of several workmen, due to the weight of such concrete burial vaults. However, in the use of the burial vault handling apparatus which forms the subject matter of the present invention a single workman is enabled to handle a concrete burial vault at the grave opening in a cemetery.

Accordingly, an object of the present invention is to provide a new and improved and relatively simple and inexpensive apparatus for handling concrete and like burial vaults and which is so constructed and arranged that in the use thereof a single workman is enabled to handle a concrete burial vault at the grave opening in a cemetery.

Another object of the present invention is to provide in the new burial vault handling apparatus a novel burial vault cover-supporting table and a supporting standard or base therefor by means of which the cover of a concrete burial vault may be supported at one side of a grave opening in a cemetery during the interment exercises in a neat and attractive manner and in such a way that it may readily be raised and moved over and lowered into the grave opening after the interment exercises.

An additional object of the invention is to provide in the new burial vault handling apparatus a novel sturdy and strong but relatively light hoist or derrick which includes a horizontal cross-beam having a pair of supporting standards or legs arranged at one end thereof and a single upright supporting standard arranged at the other end thereof.

Still another object of the invention is to provide a novel arrangement for enabling the horizontal cross beam of the new derrick to be adjusted horizontally as to length so as to enable the new derrick to be adjusted for use at grave openings of varying widths.

A further object of the invention is to provide in the new burial vault handling apparatus a

2

novel arrangement for attaching a pair of supporting legs embodied therein to one end portion of the horizontal cross beam of the derrick.

Another object of the invention is to provide in the new burial vault handling apparatus a novel arrangement for adjustably mounting a pair of auxiliary supporting legs upon the horizontal cross beam of the derrick, between the ends of the latter, so as to enable the said auxiliary supporting legs to be adjusted upon and relative to the horizontal cross beam of the derrick and thus accommodated to grave openings of varying widths.

An additional object of the invention is to provide in the new burial vault handling apparatus a novel device for holding the trolley in proper and upright position upon the horizontal cross beam of the derrick and against lateral swinging motion thereon when the trolley and the chain and pulley unit carried thereby are in use.

Other and further objects of the present invention will be apparent from the following description and claim and are illustrated in the accompanying drawings which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claim.

Fig. 1 is a side elevational view of the new burial vault handling apparatus showing the same assembled at a grave opening in a cemetery, showing the box-like body of a concrete burial vault arranged in position to be lowered into a grave opening, and showing the cover of the said concrete burial vault moved into position atop the vault cover-supporting table which is embodied in the present invention.

Fig. 2 is a view similar to Fig. 1 but showing the relative positions of the parts of the new burial vault handling apparatus when the box-like body of the vault is being lowered into the grave opening.

Fig. 3 is an end elevational view of the new burial vault handling apparatus as seen from the right hand end in Fig. 1;

Fig. 4 is a top plan view, on line 4—4 in Fig. 1, of the new concrete burial vault cover-supporting table which is embodied in the present invention;

Fig. 5 is a fragmentary sectional detail view,

on line 5—5 in Fig. 2, illustrating the trolley and horizontal cross beam of the derrick embodied in the new concrete burial vault handling apparatus and illustrating the means by which the trolley is maintained in proper upright position on the horizontal cross beam of the derrick and against lateral swinging or tilting movement thereon;

Fig. 6 is a sectional detail view, on line 6—6 in Fig. 4, illustrating certain features of the new concrete burial vault cover - supporting table which is embodied in the present invention;

Fig. 7 is a view, on line 7—7 in Fig. 4, partly in section and partly in elevation, illustrating certain features of construction embodied in the new concrete burial vault cover-supporting table which is embodied in the new concrete burial vault handling apparatus;

Fig. 8 is a view on line 8—8 in Fig. 7, partly in section and partly in elevation, of the new concrete burial vault cover-supporting table which is embodied in the present invention;

Fig. 9 is a fragmentary detail view, on line 9—9 in Fig. 1, illustrating the manner in which certain parts of the supporting legs which are arranged at one end of the horizontal cross beam of the derrick are attached thereto; and

Fig. 10 is a fragmentary detail view, on line 10—10 in Fig. 1, partly in section and partly in elevation, and illustrating the manner in which the upper section of the single upright supporting standard which is arranged at one end of the horizontal cross beam is detachably attached thereto.

A typical embodiment of the new burial vault handling apparatus is illustrated in the drawings, wherein it is generally indicated at 11, and comprises a derrick 12 which embodies a horizontal cross beam 13, a pair of upright supporting members 14 arranged at one end of the horizontal cross beam 13, a single upright supporting standard 15 arranged at the opposite end of the horizontal cross beam 13, a pair of auxiliary upright supporting members 16 which are adapted to be arranged between the ends of the horizontal cross beam 12, a trolley unit 17, a chain and pulley unit 18 carried by the trolley unit 17, and a concrete burial vault cover-supporting table 19.

The horizontal cross beam 13 of the derrick 12 includes a main outer tubular section in the form of a metal pipe 20 which provides a trackway for the trolley unit 17, a second and intermediate tubular section or pipe 21 which extends into the outer tubular section 20, and an innermost tubular section 22 which extends from the upright supporting members 14 into the intermediate tubular section 21 to a point beyond the point at which the auxiliary supporting members are arranged, when in use, so as to strengthen and reinforce the horizontal cross beam 13 of the derrick 12 throughout that portion thereof which spans the grave opening, during the operation of lowering the box-like body of a concrete burial vault into a grave opening, as will be explained more fully hereinafter.

Each of the upright supporting members 14 includes a tubular strut or lower pipe section 23 and each of these tubular struts or lower pipe sections 23 is detachably attached to the horizontal cross beam 13 of the derrick 12 by means of an attaching element which includes a short pin 24 which extends downwardly through the open upper end of each tubular strut 23 for a short but substantial distance therein (Fig. 9). Each attaching element also includes a sleeve or ring 25, and each of these sleeves or rings 25 is

permanently attached to one of the pins 24, in any suitable manner, as by welding. Each of the sleeves or rings encircles the intermediate tubular section of pipe 21 of the horizontal cross beam 13 of the derrick 12. The sleeves or rings 25 are arranged in side by side relationship on the intermediate tubular section of pipe 21 which is embodied in the horizontal cross beam 13 (Figs. 1 and 2) and each sleeve or ring 25 is attached to the intermediate tubular section or pipe 21, and to the innermost smaller reinforcing tubular section 22, by means of a pair of rivets 26 (Fig. 9).

The upright supporting members 14 are connected together as a unit by a flexible element in the form of a chain 99 (Fig. 3).

The single upright supporting standard 15 includes a main upright tubular support or pipe section 27 the lower end portion of which is telescopically mounted in a short upright tubular pedestal 28 which is attached to and is mounted upon the base 57 of the burial vault cover-supporting unit 19, as will be explained more fully hereinafter. The upright supporting standard 15 also includes a short pin or tubular pipe section 29 which extends downwardly a short distance into the tubular section or pipe 27, through the open upper end thereof (Figs. 1, 2 and 10). This short tubular pin 29 has a metal collar 30 mounted thereon which encircles and is frictionally fitted onto the upper end portion of the pipe 27. The collar 30 has a pair of upwardly extending arms 31 attached thereto in any suitable manner, or formed integral therewith, and these arms 31 carry a bolt 32 which extends through suitable openings formed in the wall of the main tubular section on pipe 20 of the horizontal cross beam 13 of the derrick 12. The bolt 32 has a nut 33 mounted thereon. This arrangement enables the upright supporting standard 27 to be readily assembled in supporting relationship with the horizontal cross beam 13 of the derrick 12, as will be explained more fully hereinafter.

Each of the auxiliary upright supporting members 16 includes a lower tubular pipe section 34 and each of these lower tubular pipe sections 34 is held in assembled and supporting relationship with and upon the main tubular section 20 of the horizontal cross beam 13 of the derrick 12 by means of a slip ring 36 having a pin 35 attached thereto and depending therefrom. Each of the pins 35 extends downwardly a short but substantial distance into the corresponding tubular pipe section 34 through the open upper end thereof (Fig. 2).

The slip rings 36 are arranged in side by side relationship upon the main outer tubular pipe section 20 of the horizontal cross beam 13 of the derrick 12 and are slidably mounted thereon so that the auxiliary supporting members 16 may be adapted and positioned, relative to the supporting members 14, at opposite sides of a grave opening, as shown in Fig. 2, and thus used in conjunction with grave openings of varying widths, as will be explained more fully hereinafter.

The trolley unit 17 includes a main supporting frame 38 which comprises a pair of spaced and generally triangular-shaped side plates 39 having a pair of spaced trolley wheels or rollers 40 provided therebetween at the ends thereof. These trolley wheels or rollers 40 ride upon the main and outer pipe section 20 of the horizontal cross beam 13 of the derrick 12 which provides a trackway therefor.

A chain and pulley supporting member 41 extends between the side plates 39 of the trolley frame 38 and this chain and pulley supporting member 41 has a centrally arranged recess 42 formed therein. The chain and pulley supporting member 41 is supported between the side plates 39 of the trolley frame 38 by a bolt 43 (Fig. 5).

In order to maintain the trolley unit 17 in upright position upon the main outer pipe section 20 of the horizontal cross beam 13 of the derrick 12, and against lateral swinging or tilting motion thereon during the process of raising and lowering the box-like body and cover of a concrete burial vault, a latch bolt 44 is threaded into a threaded opening 45 provided in one of the side plates 39 of the trolley frame 38. The inner end portion of the latch bolt 44 has an enlarged substantially square bearing head or plate 107 attached thereto in any manner, as by welding, and this bearing head or plate 107 is latchingly engageable with the outer surface of the main tubular pipe section 20 of the horizontal cross beam 13 of the derrick 12, as shown in Fig. 5. The latch bolt 45 is provided at its outer end with an enlarged hand grip head 46 to facilitate operation thereof.

The chain and pulley and chain unit 18 is of conventional construction and includes a hook 47 by which the said chain and pulley unit 18 is suspended from the central recess or notch 42 in the transverse supporting member 41 of the trolley unit 17. The chain and pulley unit 18 includes a pulley 48 and a main chain 49 carried thereby and a plurality of spreader chains 50, which are shown as being four in number. Each of the spreader chains 50 has a hook 51 attached thereto at the end thereof and each of these hooks 51 is adapted to be engaged with a corresponding one of a plurality of eye members 52, four in number, which are anchored in a rectangular pattern in the concrete of a concrete burial vault cover 53. Likewise, each of the hooks 51 on the spreader chains 50 is adapted to be engaged with a corresponding one of four eye members 54 which are anchored, in a rectangular pattern in the bottom 55 of the box-like body 56 of a concrete burial vault (Fig. 2).

The new concrete burial vault-cover supporting table 19, which is embodied in and forms an important part of the present invention, includes a supporting base 57, which may be made of wood or metal. A base plate or flange 58 is formed on the tubular base 28 of the upright supporting standard 15 and this base plate or flange 58 is attached to the supporting base 57 in any suitable manner, as by being bolted thereto, as at 59 (Figs. 4 and 8). The supporting base 57 of the concrete burial vault cover-supporting unit 19 has a second upright tubular metal section or supporting standard 60 mounted thereon, in spaced relationship with the tubular supporting standard 28. This tubular supporting standard 60 has a base flange 61 formed thereon which is bolted, as at 62, to the supporting base 57. The two upright tubular supporting standards 28 and 60 are interconnected by means of upper and lower metal cross braces 63 and 64 which are connected to the tubular supporting standards 28 and 60 in any suitable manner, as by welding.

The lower tubular metal standard 60 has an upper tubular metal section or pipe 65 telescopically mounted therein and the central turntable portion 66 of the concrete burial vault cover-supporting table 19 is mounted on the upper end por-

tion of this upper tubular pipe section 65 to which it is secured in any suitable manner, as by welding. A pair of parallel frame members 67, which are substantially L-shaped in cross section, are secured to the side marginal edge portions of the central turntable portion 66 of the concrete burial vault cover-supporting table unit 19 and are secured thereto in any suitable manner, as by welding. The central turntable portion 66 of the concrete burial vault cover-supporting unit 19 is reinforced by four radially extending brace members 68 which are arranged therebelow. These brace members 68 are preferably formed integral with the central turntable section 66 and are preferably welded at their inner and outer ends, respectively, to the tubular section 65 and to the depending flange of the parallel, L-shaped frame members 67 (Figs. 4 and 8).

As shown in Fig. 4, the L-shaped frame members 67 extend outwardly beyond the side edges of the substantially square central section 66 of the vault cover-supporting table unit 19, and a pair of tubular parallel side frame members 69 and 70, which are substantially square in cross section (Fig. 7), are attached to the end portions of the L-shaped frame members 67 in any suitable manner, as by welding. The horizontal flange portion 71 of an L-shaped end frame member 72 rests upon and is welded, or otherwise suitably secured, to the tubular side frame members 69 and 70, at one end of the latter. (Figs. 4 and 7).

The other flange 73 of this end frame member 72 projects above the top of the vault cover-supporting table unit 19 so as to provide a stop against which one edge of a concrete burial vault cover 53 may rest when the said concrete burial vault cover 53 is supported upon the vault cover-supporting table unit 19.

The new concrete burial vault cover-supporting table unit 19, which is embodied in the present invention, embodies an extensible section 74 which includes a metal cross or end frame member 75, which is substantially L-shaped in cross section, and this cross frame member 75 extends parallel to the frame members 67 and 72 at the opposite end of the table top from the cross or end frame member 72 (Fig. 4). The extensible table top section 74 includes a pair of tubular side frame members or rails 76 and 77 which are substantially square in cross section and these tubular side frame members or rails 76 and 77 are telescopically and slidably mounted in the tubular side frame members 69 and 70, respectively, of the vault cover-supporting table unit 19, as shown in Fig. 7.

A rod 78 extends into the tubular side frame member 69, through the open end 79 thereof, and this rod 78 has an angled end portion 80 which is welded, as at 81, to the upwardly extending flange 73 of the cross or end frame member 72 (Fig. 6). This rod 78 has a threaded inner end portion 84 on which a square nut 85 is mounted, for a reason which will be explained thereafter.

The upper tubular pipe section 27 of the upright supporting unit 15 may be adjusted vertically to control the effective height of the supporting unit 15. This is accomplished by means of a pin 86 which is selectively insertible into and through aligned or registered openings 87 which are formed at spaced vertical intervals or heights in the upper tubular pipe section 27. When thus inserted through a selected pair of the openings 87 in the upper tubular section 27 of the supporting unit 15 the pin 86 rests upon the upper

end portion of the lower tubular pipe section on standard 28 of the supporting unit 15, as shown in Fig. 8. The pin 86 is attached, by a flexible element in the form of a chain 89, to a bolt 90 which is mounted in lower portion of the upper tubular section 27 of the supporting unit 15.

The upper tubular section 65 of the vault cover-supporting table unit 19 is adjustable vertically relative to the lower tubular section 60, so as to control the height of the vault cover-supporting table unit 19. This is accomplished by means of a pin 91 which is selectively insertible into any one of a plurality of vertically spaced pairs of aligned or registered openings 92 which are formed in the inner tubular section 65, as shown in Fig. 8. When so disposed the pin 91 rests in a pair of substantially V-shaped notches or recesses 93 which are formed in the upper edge of the outer and lower tubular pipe section 60 in which the said substantially V-shaped notches or recesses 93 are spaced 180° apart. The pin 91 is attached, by a chain 94, to one of the cross braces 68 of the vault cover-supporting table unit 19 (Fig. 8).

As shown in Fig. 8, the open upper end of each of the lower tubular metal standards 60 and 28 may be closed when not in use, so as to keep out earth thrown up from the grave opening, as will be explained hereinafter. This is accomplished by closure members 95. Each of the closure members 95 includes a top cap plate 96 on the lower surface of which there is formed an annular collar 97 which is adapted to be frictionally fitted onto the upper end portion of one of the tubular standards 60 and 28 on the outer side thereof. Each of the closure members 95 is suspended by a chain 98 from the cross brace 93 of the table unit 19, when not in use.

A cross pin 106 is permanently attached to the upper tubular section 65 for engagement in the notches or recesses 93, as will be explained hereafter.

The use and operation of the new concrete burial vault handling apparatus are as follows:

The concrete burial vault cover-supporting table unit 19 may be arranged upon the ground 103 at one side of a grave opening 102 in a cemetery. The closure members 95 may then be arranged upon the open upper ends of the tubular standards 28 and 60 to keep out earth thrown up from the grave opening. The grave opening 102 may then be dug and the earth 104 therefrom thrown up around the concrete burial vault cover-supporting unit 19, as is shown in Fig. 1, whereupon the closure members 95 may be removed from the tubular standards 28 and 60.

A concrete burial vault 53—56 may be transported into position adjacent a grave opening 102 in a cemetery and laid upon cross planks 105 which are, in turn, laid upon planks 100 and 101 which are laid lengthwise upon the ground 103 at the sides of the grave opening 102 (Fig. 1). The parts 74—75—69—70—76—77—78, etc., of the frame of the vault cover-supporting unit 19 being assembled, the upper tubular section 65 may be inserted into the lower tubular section 60 and the upper tubular section 27 of the vault cover-supporting unit 15 may be inserted in the lower tubular section or standard 28 of the supporting unit 15. The pin 29 may then be inserted into the upper tubular section 27 of the supporting unit 15, through the open upper end thereof, and the collar 30 frictionally inserted over the upper end portion of the tubular section 27 of the supporting unit 15. One end portion of the outermost

pipe section 20 of the horizontal cross beam 13 of the derrick 12 may then be attached, by the bolt 32 and nut 33, to the upright carrier arms 31 which are attached to the collar 30.

The slip rings 36 and attached pins 35 for the auxiliary supporting members 16 may then be slid onto the outermost and main tubular section 20 of the horizontal cross beam 13 of the derrick 12 and the trolley unit 17 mounted upon the outermost tubular section 20 of the horizontal cross beam 13.

The intermediate tubular section 21 and enclosed innermost tubular section 22 may then be inserted into the outermost tubular section 20 of the horizontal cross beam 13 and the pins 24 inserted into the upper end portions of the tubular struts 23 whereupon the tubular struts 23 of the supporting members 14 may be spread apart to the limit permitted by the connecting chain 99. The lower end portions of the tubular struts 23 may be rested upon a wooden plank 100, which is laid lengthwise along one side edge of the grave opening 102, as shown in Fig. 1. The chain and pulley unit 18 may then be attached to the trolley unit 18, by engaging the hook 47 in the central recessed or notched portion 42 of the cross supporting member 41 (Fig. 5) whereupon the trolley unit 17 and the chain and pulley unit 19 suspended therefrom may then be moved along the main and outer tubular pipe section 20 of the horizontal beam 13 of the derrick 12, as a trackway, into position above the concrete burial vault 56—53. The hooks 51, which are carried by the spreader chains 50, may then be attached to the eye members 52 in the concrete vault cover 53, whereupon the concrete vault cover 53 may be lifted by the chain and pulley unit 18, from the box-like body 56 of the concrete burial vault and transported, by the trolley unit 18 and chain and pulley unit 18, into a position above the vault cover-supporting table unit 19 onto which the vault cover 53 is then lowered by the chain and pulley unit 18. The hooks 51 may then be removed from eye members 52 in the vault cover 53 and the trolley unit 18 and attached chain and pulley unit 19 may then be run back along the horizontal cross beam or trackway 20 of the derrick 12 into position above the box-like body 56 of the concrete vault 56—53. The slip rings 36 and attached pins 35 may then be slid along the main tubular section 20 of the horizontal cross beam 13 of the derrick 12 into a position above the plank 101 and the pins 35 then inserted into the open upper end portions of the tubular struts or auxiliary supporting members 34 which may then be rested on the plank 101. The hooks 51 carried by the spreader chains 50 may then be attached to the eye members 54 which are embedded in the bottom 54 of the concrete box-like body 56 of the burial vault 56—53 whereupon the box-like body 56 of the concrete burial vault 56—53 may be raised, by the chain and pulley unit 18, slightly above the supporting planks 105, and the latter removed. The chain and pulley unit 18 may then be manipulated so as to lower the box-like body 56 of the concrete burial vault into the grave opening 102, as shown in Fig. 2, whereupon the hooks 51 on the spreader chains 50 may be removed from the eye members 54 and the chains 49—50 raised up out of the grave opening 102. The chain and pulley unit 18 may then be detached from the trolley unit 17 by detaching the hook 47 from the notched cross member 41—42. The left hand end portion of the horizontal cross beam 13 of the derrick 12, as

seen in Fig. 2, may then be raised slightly and the pins 24 removed from the tubular supporting members 23 and the pins 35 removed from the tubular struts 34 of the auxiliary supporting members 16. The tubular supporting members 23 may then be removed from the plank 100 and the auxiliary tubular supporting members 34 removed from the plank 101. The rings 25 and attached pins 24 and the attached tubular section 21 and attached tubular reenforcing section 22 of the horizontal cross beam 13 may then be separated, as a unit, from the main outer tubular section 20 of the horizontal cross beam 13 and the trolley unit 17 then removed therefrom. The bolt 32 and nut 33 may then be removed and the main tubular unit or section 20 of the horizontal cross beam 13 thus detached from the tubular upper section 27 of the supporting unit 15. The tubular upper section 27 may then be lifted up out of the tubular standard 28 in which it rests, thus completing the disassembling of the new burial vault handling apparatus, in preparation for the interment exercises.

During the interment exercises the planks 100 and 101 may be allowed to remain at the sides of the grave opening 102 since they may be used during the interment exercises to support the casket-lowering device.

The concrete burial vault cover 53 is allowed to remain upon the vault cover-supporting table unit 19 during the interment exercises and when so arranged is disposed in a horizontal position so that the name of the deceased and such religious or fraternal emblem as are customarily arranged upon the top of the burial vault cover 53 may be readily seen by persons attending the interment exercises. At this time the mound of earth 104 around the vault cover-supporting table unit 19 will be covered by a grass mat.

During the interment exercises the extension 74 and the vault cover-supporting table unit 19 provides a support which the pallbearers may grasp to steady themselves when lowering the casket onto the casket-lowering device (not shown) which is rested upon the planks 100 and 101.

After the interment exercises the parts of the new derrick or hoist may be reassembled, as to Fig. 1, and the hooks 51 on the spreader chains 50 attached to the eye members 52 on the burial vault cover 53. The burial vault cover 53 may then be raised by the chain and pulley unit 18 and transported by the trolley unit 17 and chain and pulley unit 18 into a position above the grave opening 102, whereupon the burial vault cover 53 may then be lowered into the grave opening 102 and onto the box-like body 56 of the burial vault disposed therein. The new derrick may then be disassembled and the grave opening 102 filled by the earth 104 previously thrown up around the vault cover-supporting table unit 19.

During the operation of raising and lowering the vault cover 53, and the box-like body 56 of the concrete burial vault 56—53, the trolley unit 17 may be secured to the horizontal cross beam 13, and against rocking or tilting motion thereon, by manipulating the squared bearing head or inner end portion of the screw or bolt 44 into bearing engagement with the wall of the main outer tubular section 20 of the horizontal cross beam 13. This may be accomplished by grasping the handle 46 on the clamping 44 and manipulating the latter.

The new concrete burial vault cover-supporting table unit 19 may be adjusted to accommo-

date vault covers of varying widths by telescopically inserting the tubular side frame sections 76 and 77 into the tubular side frame sections 69 and 70, respectively, in the case of relatively narrow vault covers, or, in the case of relatively wider vault covers, by withdrawing the extensible table top section 74 relative to the main frame of the vault cover supporting table unit 19. During this operation the tubular side frame sections 76 and 77 slide in the tubular side frame sections 69 and 70, respectively, and outward movement of the extensible table top section 74 is limited by the engagement of the square nut 85 on the rod 78 with the end wall 83 of the tubular side frame section 76 (Fig. 6).

The tubular supporting member 65, and the vault cover-supporting table unit carried thereby, and the vault cover 53 resting thereon, may be rotated upon and relative to the lower tubular standard 60 upon which these parts are supported. This may be accomplished by manual pressure applied to the vault cover 53, and the vault cover-supporting table on which the vault cover rests, which will cause the pin 91 to ride out of the notches or recesses 93 in the upper edge of the tubular standard 60. Further manual force applied to the vault supporting table unit 19, and to the vault cover 53 disposed thereon, will rotate the upper tubular section 65 and the vault cover supporting table unit 19 carried thereby, upon and relative to the lower tubular section 60. This may be necessary prior to the interment exercises if the workmen should place the burial vault cover 53 on the vault supporting table unit 19 in a reversed position relative to the head and foot of the grave opening 102. Thus the burial vault cover 53 may be rotated through 180° on its supporting table unit 19, to position the burial vault cover 53 relative to the head and foot of the grave opening 102, without the necessity for reassembling the derrick or hoist 12 to accomplish this result. It will be understood that this is an important aspect of the present invention since the name of the deceased and such religious or fraternal or other emblems are customarily placed upon the top of concrete vault covers are arranged in a predetermined relationship relative to the head and foot of the burial vault and the grave opening.

When it is desired to have the main supporting frame of the vault cover-supporting table 19 disposed in its lowermost position the pin 91 may be allowed to hang idly on its supporting chain 94 and the pin 106 rested in the notches or recesses 93 which are formed in the upper edge of the upper tubular section 65. When so disposed the main frame of the burial vault cover-supporting unit 19, table and the burial vault cover 53 disposed thereon, may be rotated relative to the lower tubular standard 60.

The main frame of the new burial vault cover-supporting table unit 19 may be adjusted vertically as to height, and relative to the main supporting standard 60, by inserting the pin 91 into a preselected pair of aligned openings 92. This enables the main frame of the new burial vault cover supporting-table unit 19 to be adjusted relative to the size of the earth mound 104 thrown up from the grave opening 102, and relative to other variable factors.

Similarly, the upper tubular section 27 of the supporting unit 15 may be adjusted vertically by inserting the pin 86 in a preselected pair of the openings 87 which are formed in the tubular section 27. The effective height of the hori-

zontal cross beam 13 of the derrick 12 may further be controlled by adjusting the spread of the tubular supporting members 23.

It will thus be seen from the foregoing description, considered in conjunction with the accompanying drawings, that the present invention provides a new and improved and relatively simple burial vault handling apparatus having the desirable advantages and characteristics, and accomplishing its intended object, including those hereinbefore pointed out and others which are inherent in the invention.

I claim:

Burial vault handling apparatus comprising a derrick including a horizontal cross beam including an outer tubular metal section and an intermediate tubular metal section telescopically inserted into said outer section, an inner reinforcing tubular metal section telescopically arranged within said intermediate section, a pair of rings encircling one end portion of said intermediate section in side by side relationship at one end of said cross beam, means permanently attaching said rings to said end portion of said intermediate section and to said inner reinforcing section, and means for supporting said cross beam in horizontal position above a grave opening with said cross beam unobstructed from the other end of said beam to a position over such a grave opening disposed below said one end of said beam, said last named means comprising a pair of tubular metal supporting members adapted to be arranged on one side of such a grave opening in a general inverted V-shaped formation under one end portion of said horizontal cross beam so as to support the latter, a pin attached to and de-

pending from each of said rings, each of said tubular metal supporting members including an upper end portion having an open end through which one of said pins may be inserted into each of said tubular supporting members, a pair of slip rings encircling said outer tubular metal section of said cross beam and slidably mounted thereon in side by side relation, each of said slip rings including a pin attached thereto and depending therefrom, a pair of auxiliary tubular supporting members adapted to be arranged at the other side of said grave opening between the ends of said cross beam, each of said auxiliary members including an upper end portion having an open end into which one of said latter pins may be mounted, and a single upright tubular support arranged under said other end portion of said cross beam for supporting the latter.

WILBERT W. HAASE.
